CRANK CONNECTION FOR ENGINES.

1,134,545.

Specification of Letters Patent.

Patented Apr. 6, 1915.

Application filed March 30, 1911. Serial No. 617,854.

To all whom it may concern:

Be it known that we, ROBERT S. MOORE and JAMES LEE SIMMONS, citizens of the United States, residing at Washington, in 5 the District of Columbia, have invented certain new and useful Improvements in Crank Connections for Engines, of which the following is a description, reference being had to the accompanying drawing and to the 10 letters and figures of reference marked thereon.

The invention relates to new and useful improvements in the crank connection between the piston rod, and the crank shaft 15 of the gas engine, and more especially to a gas engine having a plurality of cylinders and a plurality of piston rods all of which are connected to the same crank shaft.

An object of the invention is to provide 20 a connection for the piston rod which shall be durable in construction, comparatively free of friction and readily assembled on the crank shaft.

In the drawings which show by way of 25 illustration one embodiment of the invention, Figure 1 is a side view with parts in section, showing the connection between the piston rod and the crank shaft. Fig. 2 is a horizontal sectional view, showing in part 30 a plurality of cylinders and piston rods. Fig. 3 is a view similar to Fig. 1, showing a modified form of means for attaching the piston rods to the crank shaft. Fig. 4 is a sectional view through the crank connection. 35 Fig. 5 is a detail of the supporting collar; and Fig. 6 is a detail of the retaining pin.

In the drawings we have shown the invention as applied to a seven cylinder gas engine wherein the cylinders 1 are connected 40 to a casing 2 which is mounted to rotate on a shaft 3 which is held stationary. The shaft 3 carries a crank arm 4. A second crank arm 5 is connected to the shaft 6 which is in line with the shaft 3, and on which 45 also is journaled the casing 2. The crank arm 4, carries a crank shaft 7, which may be rigidly secured thereto in any desired way. The other end of the crank shaft 7 is connected to the crank arm 5. As herein 50 shown we have provided the crank arm 5 with an inwardly projecting sleeve which fits the crank shaft 7 and said crank arm is secured to the crank shaft by a locking pin 8. In each cylinder is a piston 9, to which 55 is pivotally connected a piston rod 10. The

piston rod 10 is provided adjacent the crank shaft with laterally projecting shoulders 11 and with centrally projecting portion 12 which is formed with an opening adapted to receive a sleeve 13, carried by the crank 60 shaft 7. A pair of collars 14 are mounted on the crank shaft 7, or the inwardly projecting sleeves carried by the crank arms, and said collars are each provided with a race-way for anti-friction balls 15. A pair 65 of collars 16 surround the crank shaft, and are each provided with a race-way corresponding to the race-way in the collars 14 and adapted to receive the anti-friction balls 15. These collars 16 are each formed with 70 an inwardly projecting part 17 which engages a seat in the sleeve 13. Each of said collars is also provided with an outwardly projecting angular flange 18. These collars 16 are of such size as to fit underneath the shoulders on the piston rod. It will thus be seen 75 that the inward thrust of the piston rod will be conveyed through said shoulders 11 to the collars 16, and will be taken up by the anti-friction balls 15 resting against the 80 collars 14 on the crank shaft.

The opening in the central member 12 of the piston rod, is made sufficiently large so that the thrust of the piston is taken up entirely by the anti-friction balls. The 85 object of this central portion of the piston rod is merely to keep the piston rod properly centered relative to the crank shaft and insure the thrust being directly in line therewith. Mounted on each of the collars 16 is a second collar 19 which is formed with 90 a central portion adapted to engage the outer faces of the shoulders 11 on the piston rod 10. The inwardly projecting parts of the collars 19 engage behind the annular 95 flanges on the collars 16, so that the collars 19 are held in engagement with the shoulders on the piston rod. Any downward thrust on the piston rod due to centrifugal force in the rotation of the cylinders, will 100 be taken up by these collars 19 and received by the anti-friction balls which support the collar 16. The inwardly projecting portions 12 on the various piston rods are so disposed as to nest side by side between the collars 16 as clearly shown in Fig. 1.

In assembling the parts, one of the crank arms is attached to the crank shaft if not made integral therewith. The collar 14 and the collars 16 and 19 are assembled and 110

placed on the crank shaft at one side thereof against the crank arm. The piston rods are then put in place on the sleeve 13 on the crank shaft. Then the other set of collars 5 and anti-friction balls are placed on the crank shaft and finally the other crank arm secured to the crank shaft by the locking pin 8. It will thus be seen that the entire parts for connecting the piston rod to the 10 crank shaft are held in place by the crank arms. The entire inner and outer thrust on the piston rod is taken up by the anti-friction balls through the collar connections with the crank shaft. The piston rod is 15 merely kept in proper line with the crank shaft by the direct connection through the piston rod and crank shaft.

In Figs. 3, 4, 5, and 6 is shown a slightly modified form of the invention. The piston rod 10 is formed integral with a central member 20 which is cut away so as to form 20 seats 21 for the connections of the other piston rods. The central member 20 is attached to a collar 22 and each of the piston 25 rods except the one which is integrally attached to the central member, are held in their seats on the central member by pivot pins 23. The collar 22 is formed with outwardly projecting lugs 24 which receive the 30 pivot pins 23. The collar 22 in a measure takes the place of the laterally projecting shoulders on the piston rods 10 in the form of the invention shown in Figs. 1 and 2. Located within each collar 22 is a pair of 35 collars 25 and 26 between which are placed anti-friction balls 27 which run in raceways in said collars. In assembling these parts, the same method is followed as described in connection with Figs. 1 and 2, 40 and the parts are all held in place by the crank arms through their connection with the crank shaft. It will be noted that the entire thrust on the piston rods will be taken up by the collars 22 and through the collars 45 22 conveyed through the anti-friction balls to the crank shaft.

It is obvious that minor changes in the details of construction may be made without departing from the spirit of the invention 50 as set forth in the appended claims.

Having thus particularly described our invention, what we claim as new and desire to secure by Letters Patent, is:—

1. An engine including in combination, a 55 crank shaft, a piston rod having laterally projecting shoulders, a pair of collars surrounding the crank shaft and engaging respectively the inner faces of said shoulders, friction balls between the collars and the 60 crank shaft, a second pair of collars surrounding said crank shaft and engaging respectively the outer face of said shoulder, said piston rod having an inwardly project-

ing member provided with an opening to receive the crank shaft.

2. An engine including in combination a crank shaft, a plurality of piston rods each of which is provided with laterally projecting shoulders, a pair of collars surrounding the crank shaft and engaging respectively the inner face of each of said shoulders on one side of the piston rod, friction balls between the collars and the crank shaft, a second pair of collars surrounding the crank shaft, and engaging respectively the outer faces of each of said shoulders on one side of the piston rods, each of said piston rods having an inwardly projecting member provided with an opening to receive the crank shaft.

3. An engine including in combination, a plurality of piston rods each having laterally projecting shoulders, a pair of collars surrounding the crank shaft and engaging the inner faces of said shoulders, a second pair of collars mounted on the crank shaft and located within said first named collars, anti-friction balls between said collars, on the crank shaft, and said first named collars, a third pair of collars carried by the first named collars and engaging the outer face of said shoulders, each of said piston rods having an inwardly projecting part provided with an opening to receive the crank shaft, said inwardly projecting parts on the pistons being disposed side by side on the crank shaft.

4. An engine including in combination, a plurality of piston rods each having laterally projecting shoulders, a pair of collars surrounding the crank shaft and engaging the inner faces of said shoulders, a second pair of collars mounted on the crank shaft and located within said first named collars, anti-friction balls between said collars on the crank shaft and said first named collar, a third pair of collars carried by the first named collars and engaging the outer faces of said shoulders, each of said piston rods having an inwardly projecting part provided with an opening to receive the crank shaft, said inwardly projecting parts on the pistons being disposed side by side on the crank shaft, crank arms carrying said 100 crank shaft, one of said crank arms being detachably connected with the crank shaft, whereby said collars may be assembled on the crank shaft and held thereon by the crank shaft.

In testimony whereof we affix our signatures, in presence of two witnesses.
